UNITED STATES PATENT OFFICE

BENJAMIN J. FRIEDMAN, OF NEW YORK, N. Y.

DESIGN FOR AN EDIBLE PRODUCT

Application filed January 13, 1933. Serial No. 46,820. Term of patent 14 years.

To all whom it may concern:

Be it known that I, BENJAMIN J. FRIEDMAN, a citizen of the United States, and a resident of the city of New York (borough of Manhattan), in the county and State of New York, have invented the new, original, and ornamental Design for an Edible Product, of which the following is a specification.

Reference is had to the accompanying drawing, in which

Figure 1 is a top plan view of an edible product showing my new design.

Figure 2 is a side view thereof.

Figure 3 is an end view thereof.

Figure 4 is an opposite end view.

I claim:

The ornamental design for an edible product substantially as shown.

BENJAMIN J. FRIEDMAN.
